Primary Examiner — Elizabeth J Oswecki(74) *Attorney, Agent, or Firm* — Harness, Dickey & Pierce, P.L.C.(57) **CLAIM**

The ornamental design for an automated teller machine, as shown and described.

DESCRIPTION

FIG. 1 is a front view of a first embodiment of an automated teller machine showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top, left side perspective view thereof;

FIG. 8 is another top, left side perspective view thereof, adjacent environmental structure shown in broken lines;

FIG. 9 is a front view of a second embodiment of an automated teller machine showing our new design;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a top, left side perspective view thereof; and,

FIG. 16 is another top, left side perspective view thereof, adjacent environmental structure shown in broken lines.

The broken lines are for illustrative purposes only and do not form part of the claimed design.
